UNITED STATES PATENT OFFICE.

ALBERT B. CLISSON, OF GEDDES, NEW YORK, ASSIGNOR, BY MESNE ASSIGNMENTS, TO LIBERTY NATIONAL BANK, TRUSTEE, OF SYRACUSE, NEW YORK.

PRESSING MACHINE.

Application filed November 27, 1923. Serial No. 677,251.

To all whom it may concern:

Be it known that I, ALBERT B. CLISSON, a citizen of the United States, and a resident of Geddes, in the county of Onondaga and 5 State of New York, have invented a certain new and useful Pressing Machine, of which the following is a specification.

This invention relates to pressing machines as garment and laundry pressing 10 machines and has for its object a particularly simple and efficient motion transmitting mechanism for controlling the application of heavy pressure by power mechanism.

The invention consists in the novel features and in the combination and construction hereinafter set forth and claimed.

In describing this invention, reference is had to the accompanying drawings in which like characters designate corresponding 20 parts in all the views.

Figure 1 is a side elevation of a pressing machine embodying my invention.

Figure 2 is a large sectional plan view line 2—2, Figure 1 showing the means for 25 effecting the connection and disconnection of the power shaft and motion transmitting mechanism.

Figure 3 is a detail view of the cam.

Figure 4 is a face view of the latch plate. 30 Figure 5 is a face view of the pressure member which coacts with the latch plate.

Figure 6 is a fragmentary view of the portion of the manual means for operating the clutch.

35 This pressing machine comprises generally a pair of coacting pressing elements having relative movement one toward and from the other, the movable element being movable by the operator from the open position toward pressing position, power means for actuating the movable element to apply heavy pressure after the movable element has been moved by hand toward the other element motion transmitting means between 40 the power means and movable element comprising an intermittently movable cam and a member having a follower coacting with the cam for transmitting the motion of the cam to the movable element and manual means for connecting and disconnecting the power means and the cam.

45 1 designates the frame of the machine which may be of any suitable form, size and construction, it having a table 2 on which 50 is supported a neck or bracket 3. 4 and 5

are the pressing elements, the element 5 being movable toward and from the element 4. The element 4 is usually called the lower buck and is mounted upon the bracket 3. The movable element 5 is a head movable 60 toward and from the buck 4. The buck 4 and head 5 are usually formed hollow and are connected in a steam system and either one or both may be provided with perforations in the face thereof in which steam can 65 be ejected, if desired, on the articles being pressed.

The press head 5 is here shown as supported by a lever or yoke 6, this lever being pivoted between its ends at 7 to a standard 70 8 rising from the rear end of the frame 1, the lever having rearwardly and forwardly extending arms 9, 10. The press head is carried in any suitable manner by the forward arms 10. 75

The power means preferably comprises a constantly rotating shaft 11, which is connected to a shaft of constantly running motor A on the shaft of which a flywheel B is mounted. The shaft 11 is in alignment 80 with the motor A and is an extension of the armature shaft of the motor. The shaft 11 is, also, shown as formed with a worm 12 thereon, meshing with the worm gear 13 loosely mounted or mounted to rotate about 85 a shaft 14. The shafts 11, 14, the worm and worm wheel 12, 13 and the half revolution or periodic clutch, to be presently described, are to be suitably supported in a casing 15, supported in any suitable manner by the 90 frame 1.

The motion transmitting means between the shaft 11 and the press head 4, in addition to the lever 6 comprise toggle links 17, 18 pivoted together at 19 and pivoted respectively at 20, 21 to the rear arm 9 of the lever 6 and to the lower end frame 1, a member or lever 22 extending forwardly from the link 18, the shaft 14 before mentioned, an intermittently movable cam 23 mounted on the shaft 14 and a member 24 carried by the lever arm 22 and coacting with the cam. The cam 23 or shaft 14 is connected or clutched to the shaft 11 or worm gear 13 rotatable with the shaft 11 by operator 105 actuated means to be hereinafter described.

A suitable counter weight 25 may be carried by the rear arm 9 of the lever 6 and the lever 6 at the front end thereof or the press head, 5 is provided with a handle 26 at the 110

front side of the press head by means of which the press head is moved from open position toward closed position or preferably to position where it overlies the garment on the lower buck 4.

The cam 23, as here shown, is a scroll cam and the member or lever 24 is provided with a follower as a roller 27. This member or lever 24, as here shown, is pivoted on forwardly and rearwardly extending axis 28 to the arm or lever 22 and is provided with laterally extended weighted arm 29, which tends to move the lever 24 on its pivot in such direction as to move the follower 27 toward the cam or low point of the peripheral cam face thereof when the lever or arm 22 has been moved downwardly by manual closing of the press head, as when the operator pulls downwardly on the handle 26. The cam 23 is, also, formed with a laterally inclined face 30 extending across the peripheral cam face for shifting the follower out of the path of the peripheral face at a predetermined point in the rotation of the cam. The weighted arm 29 normally tends to hold the roller 27 against the end face of the cam. When the press is closed by pulling down on the handle 26, the member 22 moves downwardly and, when the roller 28 comes opposite the low point of the peripheral surface of the cam, the weighted arm moves the roller under the low point of the cam, and when the clutch, to be described, is shifted to connect the cam to the constantly running motor, the cam makes a half revolution depressing the member 22 and applying pressure through the toggle links and lever 6 to the press head. When the cam has made a half revolution, the periodic clutch shifts to "off" position automatically and the cam remains engaged with the follower and holds the member 22 depressed and, hence the press head 5 in pressing position indefinitely or long enough to suit the operator. The operator then again manually shifts the periodic clutch whereupon the cam makes another half revolution and, during such half revolution, the laterally inclined face 30 thereof moves the roller out of engagement with the peripheral face of the cam whereupon the counterweight 25 opens the press. At the end of the second half revolution, the periodic clutch automatically disconnects itself from the power shaft 11.

The manual or operator operated means for controlling the actuation of the cam 23 or controlling the connection of the cam 23 to the power shaft 11 or worm gear 13 comprises a periodic or half revolution clutch having a section 31 connected to the cam 23 and a section rotatable with the worm gear 13, and manual means for engaging and disengaging the clutch sections. The clutch here shown is a disk clutch and the driven

section 31 associated with the cam 23 comprises a hub keyed to the shaft 14 and a series of disks 33 slidably interlocked or keyed to the hub, and the driving clutch section rotatable with the worm gear 13 comprises disks 35 interleaved with former disks 33 and slidably keyed to arms 36 extending from the worm gear 13 parallel with the shaft 14. The clutch further includes a pressure ring 37 keyed to the clutch section 31 and pressing against the disks and a second pressure ring 38 mounted on the shaft 14 and opposed to the first pressure ring, springs 39 interposed between the pressure rings, a latch plate 40 fixed from rotation and formed with annular plane surface 41 concentric with the shaft 14 and with diametrically opposite notches or notches 43 coacting with teeth or rollers 44 on the second pressure ring 38 and means for shifting the second pressure ring 38 for carrying the rollers 44 out of the notches 43.

As here illustrated, the springs 39 encircle rods or studs 45 projecting from the first pressure ring 37 and through holes in the second pressure ring 38. The latch plate 40 forms a cover for the casing 15. The construction per se of the periodic clutch forms no part of this invention and any suitable periodic clutch may be used.

The shifting means, as here shown, comprises a hand lever 46 pivoted at 47 to the frame and connected by a link 48 to one arm of a bell crank lever 49, the other arm of which carries a fork 50 working in a groove 51 in the hub 52 of the second pressure ring 38. Obviously, upon the movement of the hand lever 46, the second pressure ring 38 will be shifted axially to the left, Figure 2, against the springs 39 and cause the disks 33, 35 to frictionally engage and the rollers 44 to move out of the notches 43 or the latch plate 40. Whereupon the cam 23 and the shaft 14 will be rotated with the worm wheel 13 and, in so doing, move the teeth or rollers 44 of the second pressure ring 38 along the annular face 41 of the latch plate 40 until the cam makes a half revolution when the teeth or rollers 44 again come into alignment with the notches 43 and the second pressure ring 38 is shifted axially by the springs 39, moving the teeth or rollers 44 into the notches 43 and causing the disks 33, 35 to separate or disengage. The cam thus makes a half revolution. Upon again operating the hand lever 46, the cam 23 will again make another half revolution. The first half revolution actuates the cam a half revolution and hence actuates the lever 6 to apply pressure to the head 5. The second half revolution causes the lever to be released from the holding action of the cam 23 and, during this second half revolution, the inclined face 30 of the cam forces the follower 27 out of engagement with the peripheral face of the

cam 23, so that the press head 5 is opened by the counterweight at the rear end of the lever 6.

In operation, when the press is open, the operator closes the press by pulling down on the handle 26 and thus causes the lever 6 to move downwardly until the head engages the article on the lower buck 4. During such movement, the toggle links 17, 18 are moved toward a straight line, the lever 22 is moved downwardly carrying the member 24 downwardly far enough, so that the roller 27 is shifted by the weighted arm 29 under the low point of the cam 23. The operator then actuates the hand lever 46 thus shifting the second pressure member 38 and the rollers 44 out of the notches 43 and causing the clutch disks 33, 35 to engage whereupon the cam 23 makes a half revolution, causing the head 5 to be brought down with pressure on the garment or other article on the lower buck 4, the cam 23 remaining engaged with the cam follower 27, thus holding the pressure head in its pressing position. When pressure has been applied long enough to suit the operator, he again actuates the handle 46 in the same direction as before, again engaging the clutch disks and causing the cam 23 to make another half revolution and, during this second half revolution, the laterally inclined face 30 of the cam pushes the follower 27 out of position to engage the peripheral surface of the cam, so that the counterweight is free to act and open the press.

35 What I claim is:

1. In a pressing machine, the combination of coacting pressing elements having relative movement one toward and from the other, and being movable manually preliminarily toward closed position, power means for actuating the movable element, motion transmitting means between the power means and the movable element, comprising an intermittently movable cam, a member with which said cam coacts, the cam being arranged to hold said member in its operative position assumed when pressure is being applied to the movable element, said member being provided with a follower for engaging the cam and being movable into position to engage the cam by the movement of said member effected by the preliminary closing movement of the movable element, manual means for controlling the actuation of the cam, and means for moving the follower out of engagement with the cam.

2. In a pressing machine, the combination of coacting pressing elements having relative movement one toward and from the other, power means for actuating the movable element, motion transmitting mechanism between the power means and the movable element comprising an intermittently movable cam provided with a peripheral surface and a laterally extending inclined sur-

face extending across the peripheral surface, a movable member having a follower coacting with the peripheral and lateral surfaces of the cam, the peripheral surface being shaped to move said element into pressing position and hold it in pressing position and the laterally inclined face being arranged to force the follower out of engagement with the peripheral surface to effect the opening movement of said element, and means for controlling the engagement and disengagement of the cam and power means.

3. In a pressing machine, the combination of coacting pressing elements, having relative movement toward and from the other, the movable element being movable preliminarily from open position toward closed position, power means for actuating the movable element into closed position, motion transmitting means between the power means and the movable element, comprising an intermittently movable cam, having a peripheral cam surface, a lever having a follower for coacting with the cam, and movable into position to engage the cam by the preliminary closing movement of the movable element, means for moving the follower into engagement with the cam at the end of the preliminary closing movement, means for actuating the cam to depress the lever through the follower and close the press during one movement of the cam, and means for throwing the follower out of engagement with the cam during the next movement of the cam following the movement thereof which effects the closing of the press.

4. In a pressing machine, the combination of coacting pressing elements having relative movement one toward and from the other, power means for actuating the movable element, motion transmitting mechanism between the power means and the movable element, comprising an intermittently movable cam having a peripheral cam surface and a laterally inclined surface extending across the peripheral surface, a lever having a follower coacting with the peripheral cam surface and arranged to be engaged and shifted out of engagement with the peripheral surface by the cam surface at a predetermined point in the rotation of the cam and means for connecting and disconnecting the cam and the power means.

5. In a pressing machine, the combination of coacting pressing elements having relative movement one toward and from the other, the movable element being movable manually from its open position toward its closed position, power means for applying pressure to the movable element after it has been moved toward closed position, motion transmitting means between power means and movable element comprising an intermittently movable cam and a member having a follower coacting with the cam, said

member being connected to the movable element to partake of the movement thereof whereby, when the movable element is moved manually toward closed position, said 5 member carries the follower into position to coact with the cam, and means for connecting and disconnecting the cam and the power means.

6. In a pressing machine the combination 10 of coacting pressing elements having relative movement one toward and from the other, the movable element being movable manually from its open position toward its closed position, power means for applying 15 pressure to the movable element after it has been moved toward closed position, motion transmitting means between power means and movable element comprising an intermittently movable cam having a peripheral 20 cam surface and a lateral surface extending across the peripheral surface, a member connected to the movable element to partake of the movement thereof, when being moved toward pressing position, said member having 25 a follower for coacting with the cam and normally out of position for engaging cam and movable with said member during the manual closing of the press into position at one side of the peripheral surface of the 30 cam, the follower being movable laterally

relative to the cam into coaction with the cam and being shiftable laterally out of engagement over the peripheral surface of the cam by said lateral cam surface after the cam has rotated a predetermined amount, 35 and means for connecting and disconnecting the cam and the power means.

7. In a pressing machine, the combination 40 of coacting pressing elements having relative movement one toward and from the other, the movable element being movable by hand from its open position toward closed position, power means for actuating the movable element after it has been moved toward closed position, motion transmitting 45 mechanism between the power means and the movable element comprising an intermittently movable cam having a peripheral cam surface and a laterally inclined cam surface extending across the peripheral surface at one point thereof, a lever, a follower carried by the lever and movable crosswise thereof into and out of the path of the cam and being provided with means tending to move it into the path of the cam. 50

In testimony whereof, I have hereunto signed my name, at Syracuse, in the county of Onondaga, and State of New York, this 15th day of Nov., 1923.

ALBERT B. CLISSON.
